US00D820517S

(12) **United States Design Patent** (10) Patent No.: **US D820,517 S**
(45) Date of Patent: **** Jun. 12, 2018**

(54) **COMB**

(71) Applicant: **Tsuyoshi Tanaka**, London (GB)

(72) Inventor: **Tsuyoshi Tanaka**, London (GB)

(**) Term: **15 Years**

(21) Appl. No.: **35/502,913**

(22) Filed: **Apr. 12, 2017**

(80) **Hague Agreement Data**

Int. Filing Date: **Apr. 12, 2017**

Int. Reg. No.: **DM/095741**

Int. Reg. Date: **Apr. 12, 2017**

Int. Reg. Pub. Date: **May 5, 2017**

(51) **LOC (11) Cl.** **28-03**

(52) **U.S. Cl.**

USPC **D28/21**

(58) **Field of Classification Search**

USPC D28/7, 20-34; D32/49; D30/158, 159

CPC A45D 24/00

See application file for complete search history.
